UNITED STATES PATENT OFFICE.

LAURA MCQUILLAN, OF FORT SILL, OKLAHOMA.

HAIR-WAVING TUBE.

Application filed April 8, 1924. Serial No. 705,056.

To all whom it may concern:

Be it known that I, LAURA MCQUILLAN, a citizen of the United States, and a resident of Fort Sill, Comanche County, State 5 of Oklahoma, have invented certain new and useful Improvements in Hair-Waving Tubes, of which the following is a full and clear specification.

My invention relates to that type of tube 10 which is employed in hair-waving treatments, which are now well known and need not be specifically described.

In the drawing annexed—

Fig. 1 is a perspective view of my device; 15 Fig. 2 is a perspective view of the top end of the device;

Fig. 3 is a side elevation partly broken away;

Figs. 4 and 5 are perspective views of 20 details;

Fig. 6 is a perspective view of my novel form of guard.

Fig. 7 is a sectional view taken through the clamp-screw 22 in Fig. 1.

25 Referring to the drawing annexed by reference-characters, 10 designates a metallic tube closed at its lower end except for a steam-escape opening 11 and closed at its top by means of a removable imperforate 30 cap 12 whose flange embraces the upper end of the tube, the cap being detachably locked to the tube by a bayonet slot 13 formed in the flange of the cap and a pin 14 fastened in the tube.

35 At a point opposite the pin 14, the top end of the tube is provided with a notch 15, and the corresponding part of the cap flange is provided with a registering notch 16. The strand of hair is first, as shown, enclosed

40 in a wetted fabric package or packing approximately of a size to slip easily within the tube. The strand or bunch of hair, at a point as near the scalp as possible, is arranged to lie in the slot 15. The cap is 45 then put on and locked by turning. The notch 16 in the cap-flange straddles the strand of hair. The notch 15 is long enough to permit the cap to be turned its full distance in locking it on the pin 14 without causing the hair to be pinched 50 against the vertical wall of the notch 15. The notch 15 is substantially closed by the cap-flange and by the bunch of hair lying in it. The notch 16 is narrower than the notch 15, and when the cap is in place the

bunch of hair lies in the top end of the notch. After the package of hair is thus locked in the tube, the tube is placed in an electric heater, as usual, and upon applying heat to the tube steam is generated within 60 the tube, thus causing the lotion that is usually applied to the hair to cause the hair to take a permanent wavy form.

By closing the top of the tube, I provide a steam space, thus insuring the hair being 65 thoroughly steamed at the point where it is most needed, namely, at a point near the scalp. Very little of the steam can escape through the notches 15 and 16, as these notches are virtually closed. An advan- 70 tage in having the hair passage at the side of the tube is that the tube is thus permitted to hang straight down on the strand of hair and will thus avoid exerting that undue strain on the hair which results when 75 the hair enters the top end of the tube. To avoid undue steam pressure within the tube, I provide the escape-opening 11 at the bottom thereof.

To prevent escaping steam from burning 80 the scalp, I apply a guard to the strand of hair at a point between the tube and the scalp, as shown in Fig. 3. I prefer to construct this guard of a pair of semi-circular sections 17 and 18 pivoted together 85 at one end by a pivot 19. The adjacent straight edges of the plates are correspondingly notched at 20 so that when the plates are swung to overlapped position, the notches 20 form a central hole through the 90 guard for the passage of the strand of hair. The lower plate is constructed of two pieces of metal separated by a filler-piece 21, and for locking the plates in their overlapped position, I provide a clamp-screw 22, the 95 single-ply plate 17 being provided with a notch 23 for straddling the shank of the clamp-screw.

It will be observed that the clamp-screw 100 22 passes through a hole in one of the plies of the plate 18 and is tapped into a boss on the other plate, so that by screwing-up the clamp-screw the two plies are brought into clamping relation with the intermediate single-ply plate 17.

What I claim as new is:

1. A device of the class set forth consisting of a metal tube, a removable cap enclosing one end of this tube, the cap being secured to the tube by a bayonet-slot device 110

requiring the cap to be rotated to lock it, the other being double-ply, the plies being separated, one end of the single-ply plate being pivotally mounted between the plies of the double-ply plate and the other end of this single-ply plate being provided with a clamp-screw notch, said double-ply plate being provided with a clamp-screw connecting the two plies to adapt said two plies to form a clamp for clamping the single-ply plate between them in closed position. 15
5 being sufficiently wider than the notch in the cap-flange to permit the cap to be rotated to locking position without severing the hair strand.

2. A guard for the purpose set forth, 10 consisting of a pair of plates having straight edges notched to correspond midway their length to form a hole for the hair strand, one of these plates being single-ply and the

In testimony whereof I hereunto affix my signature.

LAURA McQUILLAN.
